UNITED STATES PATENT OFFICE

JENS A. CHRISTENSEN, OF OMAHA, NEBRASKA

PNEUMATIC MATTRESS

Application filed March 19, 1929. Serial No. 348,239.

The present invention relates to improvements in pneumatic mattresses, and has for an object to provide an improved pneumatic mattress constructed for particular use in connection with metal bedsteads.

Another object of the invention resides in providing an improved pneumatic mattress for use in the home, and also in hospitals for providing body comfort during the restful 10 periods of sleeping hours.

A further object of the invention is to provide a soft flexible form-fitting mattress, which will yield a maximum refreshment to the person lying on same, and which will also 15 be impervious to moisture, such as perspiration from bed-ridden patients.

A still further object of the invention is to provide an improved mattress, which will facilitate surgical operations after which the 20 mattress may be washed and sterilized for future use.

A still further object of the invention is to provide a rectangular mattress frame, which will fit a conventional bedstead, as 25 well as the channel iron type of bedstead frames encountered in hospitals.

A still further object of the invention is to provide an improved means, whereby the air pressure may be applied and maintained 30 in pneumatic mattresses, and whereby the rubber mattress sheets employed may be secured in the frame in avoidance of leakage of the pneumatic pressure, and in which the edge portions of the sheets will be protected.

With the foregoing and other objects in view, the invention will be more fully described hereinafter, and will be more particularly pointed out in the claims appended hereto.

In the drawings, wherein like symbols refer to like or corresponding parts throughout the several views,

Figure 1 is a plan view, with parts broken away showing a pneumatic mattress constructed according to the present invention.

Figure 2 is an edge view of the same.

Figure 3 is a fragmentary vertical sectional view taken through the improved mattress.

Figure 4 is a fragmentary vertical section

taken on an enlarged scale through the pneumatic valve structure and adjacent parts.

Figure 5 is a vertical section taken through a bedstead with the improved mattress in place thereon, and with a person indicated 55 in dotted lines as recumbent upon the mattress, and

Figure 6 is a fragmentary perspective view of the liner employed.

Referring more particularly to the drawings the frame of the improved mattress is preferably composed of frame bars 10 of wood or other appropriate material and of metallic or other liners 11, which may be of sheet metal, and which extend upon the inner surfaces of the bars 10 and have webs 12 and 13 above and below the bars for the purpose of providing seats on which the rubber or other sheets 14 and 15 may be placed. The webs 12 and 13 are formed with out-turned 60 flanges 16 and 17 at their free outer edges, and the free edges of the flanges 16 are rolled or clinched over, as indicated at 18 to impart strength to these upstanding free edges and to present smooth surfaces to avoid catching and tearing the bed-clothing or marring the bedstead.

Bolts or other appropriate fastenings 19 are shown as passing through the metallic or other securing strips 20 and through the margin portions of the rubber sheets 14 and 15, through the webs 12 and the bars 10 in order to secure all of the parts together and to bind the margin of the rubber sheets in compressed condition between the pointer strips 20 and the webs 12, whereby to form an air tight joint all about the frame to avoid the leakage of the air pressure, which is contained within the central chamber formed within the rectangular frame composed of the bars 10 and the covering of the laminated sheets above and below the frame.

It will be noted that the innermost sheet 15 is preferably of greater thickness to sustain the weight of the patient while the outer sheet 14 is thinner. The inner sheets 15 are preferably substantially one-eighth of an inch in thickness; the outer sheets 14 being comparatively thinner. The bolts 19 are pro-

vided with nuts 21 by which the same may be tightened on the various parts.

Referring to Figure 4, an air valve is shown as having an externally threaded valve stem 22 threaded through openings made in one of the bars 10 and liner 11 with parts projecting upon the inner and outer surfaces of the rectangular frame. Lock nuts 23 and 24 are threaded upon the valve stem 22, the nut 23 taking against the outer surface of the bar 10; while the opposite lock nut 23 takes against the liner 11 and is preferably welded thereto.

Within the outer portion of the valve stem 22 is an internally threaded socket 25 for receiving the threaded valve head 26, which is adapted to receive a hose or other connection 27 by which the interior of the mattress may be inflated. The valve 28 may be of a collapsible rubber form, which is well known, and which is adapted to receive air from the hose 27 and admits such air to the interior of the mattress, but which may automatically collapse and close upon the fall in pressure on the exterior of the mattress.

In Figure 6 I have shown the liner 11 with the webs and flanges in perspective view, and as having the perforations 29 to receive the bolts 19.

In Figure 5 is shown a head board 30 and a foot board 31 and the bedstead frame 32 for receiving the improved pneumatic mattress. In dotted lines I have shown a person 33 as lying upon the mattress with the mattress assuming a wave-like form to fit the contour of the body and to support the body throughout. This support of the body at all surface points is found to be more restful and refreshing and less prone to setting up spinal and nerve troubles. The mattress may be used for any ordinary home purposes or it may be used in hospitals where it is valuable on account of its liquid proof qualities, and the fact that it may be sterilized readily.

I do not wish to be restricted to the size, form and proportions of the various parts, and obviously changes could be made in the construction herein described without departing from the spirit of the invention, it being only necessary that such changes fall within the scope of the appended claims:—

What is claimed is:—

1. An improved pneumatic mattress comprising a frame composed of wooden bars, and a metal liner for the bars having webs above and below the bars and flanges extending out from the webs, sheets stretched across the frame, and fastening means passing through said sheets, webs and the bars.
2. An improved pneumatic mattress comprising an open frame composed of bars, and a liner for the inside faces of the bars and having webs above and below the bars and provided with flanges outstanding from the free ends of the webs, said flanges having

overturned edges, rubber sheets stretched over said frame and having the margin portions seated on said webs and the ends protected by said flanges, strips on the sheet margins, and fastenings securing said sheets and strips to the flanges and bars.

In testimony whereof, I have affixed my signature.

JENS A. CHRISTENSEN.
